(57) **CLAIM**

The ornamental design for a display screen with animated graphical user interface, as shown and described.

DESCRIPTION

FIG. 1 is the first image in a sequence for a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof;

FIG. 16 is the sixteenth image thereof;

FIG. 17 is the seventeenth image thereof;

FIG. 18 is the eighteenth image thereof;

FIG. 19 is nineteenth image thereof;

FIG. 20 is the twentieth image thereof;

FIG. 21 is the twenty-first image thereof;

FIG. 22 is the twenty-second image thereof;

FIG. 23 is the twenty-third image thereof;

FIG. 24 is the twenty-fourth image thereof;

FIG. 25 is the twenty-fifth image thereof;

FIG. 26 is the twenty-sixth image thereof;

FIG. 27 is the twenty-seventh image thereof;

FIG. 28 is the twenty-eighth image thereof;

FIG. 29 is the twenty-ninth image thereof;

FIG. 30 is the thirtieth image thereof;

FIG. 31 is the thirty-first image thereof;

FIG. 32 is the thirty-second image thereof;

FIG. 33 is the thirty-third image thereof;

FIG. 34 is the thirty-fourth image thereof;

FIG. 35 is the thirty-fifth image thereof;

(Continued)

FIG. 36 is the thirty-sixth image thereof; FIG. 37 is the thirty-seventh image thereof; FIG. 38 is the thirty-eighth image thereof; FIG. 39 is the thirty-ninth image thereof; FIG. 40 is the fortieth image thereof; FIG. 41 is the forty-first image thereof; FIG. 42 is the forty-second image thereof; FIG. 43 is the forty-third image thereof; FIG. 44 is the forty-fourth image thereof; FIG. 45 is the forty-fifth image thereof; FIG. 46 is the forty-sixth image thereof; FIG. 47 is the forty-seventh image thereof; FIG. 48 is the forty-eighth image thereof; FIG. 49 is the forty-ninth image thereof; FIG. 50 is the fiftieth image thereof; FIG. 51 is the fifty-first image thereof; FIG. 52 is the fifty-second image thereof; FIG. 53 is the fifty-third image thereof; FIG. 54 is the fifty-fourth image thereof; FIG. 55 is the fifty-fifth image thereof; and, FIG. 56 is the fifty-sixth image thereof. The appearance of the animated graphical user interface sequentially transitions between the images shown in FIGS. 1-56. The process or period in which one image transitions to another forms no part of the claimed design. The even-length broken line showing of the text illustrates portions of the animated graphical user interface that forms no part of the claimed design. The uneven-length broken line showing of the display screen forms no part of the claimed design.
